(Model.)

G. TIETZE.

CAMP CHAIR.

No. 337,715.

Patented Mar. 9, 1886.

UNITED STATES PATENT OFFICE.

GUSTAV TIETZE, OF SAN FRANCISCO, CALIFORNIA.

CAMP-CHAIR.

SPECIFICATION forming part of Letters Patent No. 337,715, dated March 9, 1886.

Application filed April 27, 1885. Serial No. 163,551. (Model.)

To all whom it may concern:

Be it known that I, GUSTAV TIETZE, a citizen of the United States, residing at San Francisco, in the county of San Francisco and State 5 of California, have invented certain new and useful Improvements in Camp-Chairs; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved camp-chair, showing the same extended and ready for use. Fig. 2 is a longitudinal vertical sectional view of the same. Fig. 3 is a top view of the same, part of the covering having been broken away for the 20 purpose of better showing the construction. Fig. 4 is a side view showing the chair folded for transportation. Fig. 5 is a transverse sectional view taken on the line $\alpha\alpha$ in Fig. 4. Fig. 6 is a detail view in perspective and on 25 a larger scale of the jointed part of the supporting-legs or standard; and Fig. 7 is a detail view of the pivoted hinge.

The same letters refer to the same parts in all the figures.

30 This invention relates to folding chairs or camp-chairs; and it has for its object to provide a device of this class which shall possess superior advantages in point of simplicity, durability, inexpensiveness, and general efficiency, which may be easily folded up so as to occupy but little space, and which may be readily carried in the hand.

With these ends in view the invention consists in the improved construction and combination of parts, which will be hereinafter 40 fully described, and particularly pointed out in the claims.

In the drawings hereto annexed, A designates the support of my improved chair, which 45 consists of three legs, B, C, and D. The leg B has two sides at about right angles to each other, in which are sunk and secured a pair of plates, E E, to which are swiveled the plates F F, which are secured to the inner sides of 50 the legs C and D, which latter are thus attached to the leg B in such a manner as to be

capable of swinging out to the position shown in Fig. 1 of the drawings. To the front edge of the leg C is secured a laterally-extending stop, G, to intercept the leg C when the latter is either folded or unfolded. The meeting edges of the legs C and D are provided with interlocking notches H H. A stud, I, secured at the front edge of the leg B at the lower end of the latter, serves to intercept the leg D 55 when the latter is folded, and a stud, J, extending laterally from the upper end of the leg C, prevents the leg D from being unfolded prior to the said leg C. To the front edge or face of the leg B is hinged a small plate, K, 60 which, when the legs C and D are unfolded, may be swung out over the upper edge of the latter, thereby serving to retain all the legs in the position to which they have been adjusted. To the rear edge of the upper end of the leg B 65 is hinged the back-support L, which, when not in use, may be folded against the rear side of the said leg B. The upper end of the back-support has a tenon, N, adapted to enter a mortise, M, in the top piece or bar, O, which 70 latter may thus be secured in place detachably. To the said top bar, O, is secured the upper end or edge of the textile covering P, the other edge of which is secured to a cross-bar, Q, having notches R, whereby it may be 75 seated in sockets S at the upper ends of the legs C D, thus forming the front seat-rail. The back-support L is provided near its lower end with forwardly-extending perforated lugs 80 T T, extending through slits U U in the textile covering, and through which may be passed a round stick or bar, V, which latter serves to hold the covering stretched or taut and to hold the back-support elevated to its proper position. The round or bar V, when not in use, 85 is accommodated in a recess, W, formed in the adjoining sides of the leg B and back-support L when the latter is folded. The cross-bar or seat-rail Q has a small perforated plate or lug, X, which may be buttoned over a stud, Y, 90 upon the leg D when the leg-frame is folded, thus enabling the textile covering to be wound or folded around the said frame and be made fast by buttoning a pair of straps, Z Z, attached to the cross-piece O onto studs or buttons A' A', attached to the leg C. The top cross-piece, O, is also provided with a handle- 95 100

strap, B', by which the device may be readily carried when folded, as shown in Fig. 4 of the drawings.

From the foregoing description, taken in connection with the drawings hereto annexed, the operation and advantages of this invention will be readily understood.

The construction is simple and inexpensive.

The chair may in a few moments time be unfolded for use or folded, as the case may require. It affords a support for the back, which has the advantage of being slightly flexible, so as to enable the occupant of the chair to lean back to a limited extent, and it may be manufactured at a very moderate cost.

Having thus described my invention, I claim and desire to secure by Letters Patent of the United States—

1. In a camp-chair, the herein-described leg-frame, comprising the leg B, having studs G and I and hinged plate K, the leg C, having notch H and stud J, and the leg D, having notch H, the said legs C and D being connected to the said leg B by means of pairs of plates 25 swiveled together, substantially as and for the purpose herein set forth.

2. In a camp-chair, the combination, with

the leg-frame, of a back-support hinged to the upper end of one of the legs, a cross-piece adapted to be secured to the upper end of said back-support, a cross-piece adapted to be secured to the upper ends of the two remaining legs, textile covering connecting the two cross-pieces and provided with slots or slits, perforated lugs or plates extending forwardly through said slits at or near the lower end of the back-support, and a round or bar extending through said lugs in front of or above the textile covering, substantially as and for the purpose set forth.

3. The combination of the leg-frame, the rear side of one of the legs of which is provided with a recess, and the back-support hinged to the upper end of the said leg and having a corresponding recess, the two forming a receptacle when the chair-frame is folded, substantially as and for the purpose set forth.

In testimony that I claim the foregoing as my own I have hereunto affixed my signature in presence of two witnesses.

GUSTAV TIETZE.

Witnesses:

JAMES L. KING,
PAUL OEKER.
